STOVE CONTROL PANEL

Lawrence H. Wilson, Detroit, Mich., and Armour H. Titus, Jr., William J. Miller, and Elmo E. Aylor, Galesburg, Ill.

Application January 3, 1956, Serial No. 39,587

Term of patent 14 years

(Cl. D81—25)

Fig. 1 is a front elevational view of a stove control panel embodying our new design;

Fig. 2 is a sectional view taken on lines 2—2 of Fig. 1;

Fig. 3 is a partial sectional view taken on lines 3—3 of Fig. 1;

Fig. 4 is a partial sectional view taken on lines 4—4 of Fig. 1; and

Fig. 5 is a side elevational view thereof.

The essential features of our new design reside in the portions shown in full lines.

We claim:

The ornamental design for a stove control panel, as shown.
